DESIGN FOR A POWDER MITT

Josephine S. Fulkerson, Joplin, Mo., and Garland
C. McCoy, Pittsburg, Kans.

Application October 26, 1945, Serial No. 123,226

Term of patent 7 years

(Cl. D86—10)

To all whom it may concern:

Be it known that we, Josephine S. Fulkerson and Garland C. McCoy, residing at Joplin, in the county of Jasper and State of Missouri, and at Pittsburg, in the county of Crawford and State of Kansas, respectively, have invented a new, original, and ornamental Design for a Powder Mitt, of which the following is a specification, reference being had to the accompanying drawing, forming part thereof.

Figure 1 is a front elevational view of a powder mitt, showing our new design,

Figure 2 is a rear elevational view, and

Figure 3 is a vertical sectional view taken substantially on the line 3—3 of Figure 1.

We claim:

The ornamental design for a powder mitt, as shown.

JOSEPHINE S. FULKERSON.
